UNITED STATES PATENT OFFICE.

EUGENE PHELPS, OF PITCHFORK, WYOMING.

GATE-OPERATING MECHANISM.

1,175,985.

Specification of Letters Patent. Patented Mar. 21, 1916.

Application filed March 18, 1915. Serial No. 15,211.

To all whom it may concern:

Be it known that I, EUGENE PHELPS, a citizen of the United States, and a resident of Pitchfork, in the county of Park and 5 State of Wyoming, have invented a new and Improved Gate-Operating Mechanism, of which the following is a full, clear, and exact description.

This invention relates to gates, and more 10 particularly to gate operating mechanisms whereby a gate can be opened from a point at either side thereof without the driver or rider being required to get off the vehicle or horse for the purpose of manually opening 15 the gate in the ordinary manner.

The invention has for its general objects to provide a comparatively simple, inexpensive and efficient gate-operating mechanism of such design that the gate can be opened 20 at a point suitably in advance thereof, and the gate will remain open a predetermined length of time and then automatically close without any further attention on the part of 25 the person driving or riding through the gate.

A more specific object of the invention is the provision of a gate-opening means in combination with a latch releasing device operating after a given interval of time to 30 release the latch from the gate so that the latter will close automatically by means of weights or equivalent means.

Still another object of the invention is to provide a toggle device which operates to 35 swing the gate open and closed, and which when the gate is closed maintains the same rigidly in such position without the free end of the gate having to be locked to a stop post, and yet the gate cannot be forced open 40 in any way except by the operation of the toggle device.

With such objects in view, and others which will appear as the description proceeds, the invention comprises various novel 45 features of construction and arrangement of parts which will be set forth with particularity in the following description and claims appended hereto.

In the accompanying drawings, which 50 illustrate one embodiment of the invention, and wherein similar characters of reference indicate corresponding parts in all the views, Figure 1 is a perspective view of the gate in closed position; Fig. 2 is a side view of the 55 gate-operating means with the gate in closed position; Fig. 3 is a horizontal sectional view

on the line 3—3, Fig. 2; Fig. 4 is a side view of the gate-operating means with the gate in open position; Fig. 5 is an enlarged edge view of the special form of hinge for the 60 toggle device; Fig. 6 is a side view of the hinge; Fig. 7 is an enlarged sectional view on the line 7—7, Fig. 3; Fig. 8 is a sectional view of the time-controlled latch releasing device, the section being taken on the line 65 8—8, Fig. 9; Fig. 9 is a vertical section on the line 9—9, Fig. 8; and Fig. 10 is a detail sectional view of parts of the time-controlled latch releasing device.

Referring to the drawings, A designates 70 a gate of any desired construction which is hinged on a gate post 1, and the free end 2 of the gate is adapted to coöperate with a stop post 3. The gate is adapted to swing in the direction indicated by the arrow, 75 Fig. 1, and the swinging movement is accomplished by a toggle device B consisting of two bars 4 and 5 having their inner ends connected together by a hinge 6. The outer end of the bar 4 is connected by a universal 80 or equivalent joint 7 with a bracket 8 which is adjustably mounted on a vertical strip 9 fastened to the gate A. The bar 5 of the toggle device is attached to a special form 85 of hinge C which is itself fastened to a supporting post or equivalent structure D, which post is positioned along the roadside a few feet from the gate in a direction toward which the gate swings open. When 90 the gate is closed, as shown in Fig. 1, the toggle device is horizontal; or in other words, the toggle device is locked so that pressure on the gate will not affect the opening thereof, it being necessary to "break" 95 the toggle device by raising the inner ends of the bars 4 and 5 so that the toggle device as a whole will swing on the hinge C and thereby draw the gate open. As shown in Fig. 7, the bars 4 and 5, which may be made 100 of channel iron, are provided with weights 10, which, together with the weight of the bars, operate to close the gate when the same is released. The hinge C is formed with two leaves 11 and 12 of symmetrical form, 105 each leaf having a flat portion 13 and an obliquely bent skewed portion 14, such latter portion having pintle eyes 15 that receive the pintle 16. By this construction the pintle is disposed at an angle to the plane of the flat portions 13 of the leaves, and by 110 reason of this construction the toggle device can be collapsed or straightened without

binding or restraint, while the gate end of the toggle device moves in an arc of a circle around the gate post 1 as a center.

When the gate is open, as shown in Fig. 4, the toggle device B is off a vertical dead center line passing through the hinge C; or in other words, the weight of the toggle device is operative on the left side of a vertical line passing through the hinge C, and 10 as a consequence the gate will gravitate to closed position when a latch E is released. This latch is a lever pivoted at 17 to one side of its center, and on the long arm 18 is a depending hook 19 having a beveled surface 20, and this hook is disposed in the path of the lower bar 21 or equivalent part of the gate, so that as the gate swings open it will strike the beveled surface 20 of the latch and raise the latter until the hook 19 15 is cleared, when the latch will drop and thereby hold the gate in open position, as shown in Fig. 4. When the latch is released by pressing downwardly on the lighter arm 18', the gate will gravitate to closed position.

To enable the gate to be opened at a point suitably remote therefrom, a pull cable F is connected with the bar 5 of the toggle device adjacent the hinge 6, and this 30 cable is guided by pulleys 21 on the post D, and at these pulleys the cable is divided into branches f and f' extending in opposite directions from the gate, and the free end of either branch is adapted to be pulled for 35 opening the gate, and for convenience the free ends are supported on out-posts 22, whereby the handles 23 can be reached without a person dismounting from a horse or getting out of a vehicle.

40 It is desired to cause the gate to close automatically, and therefore a time-controlled latch releasing device G is employed. This device G comprises a vertically movable bar 24 carrying a weight 25, and on the lower 45 end of the bar is a foot 26, arranged to engage the latch E to release the same when the bar moves downwardly. The upper end of the bar is connected with the cable F, so that as the latter is pulled to open the gate 50 the bar 24 is raised. This bar 24 has rack teeth 27 which mesh with a pinion 28 on a shaft 29 mounted in a box 30, and on this shaft in a loose gear wheel 31 that in turn meshes with a pinion 32 on a shaft 33 in 55 the box 30. This shaft 33 operates through a worm wheel 34, and worm 35, a retarding fan 36 which determines the rate of movement of the rack bar downwardly to release the latch. The gear 31 has a spring-pressed 60 pawl 37 which engages a ratchet wheel 38 on the shaft 29, whereby the gear wheel will rotate with the shaft 29 in one direction only, or when the rack bar is descending, but during the upward movement of the rack 65 bar the gear wheel 31 is idle, so that the re-

tarding device 36 will not interfere with the quick upward movement of the rack bar, as when the gate is being thrown open. The parts are so designed that the gate will remain open for a sufficient length of time to 70 permit a person to drive or ride through the gateway, and then the gate will automatically close, since the time-controlled mechanism G will release the latch E.

From the foregoing description taken in 75 connection with the accompanying drawings, the advantages of the construction and method of operation will be readily understood by those skilled in the art to which the invention appertains, and while I have 80 described the principle of operation, together with the mechanism which I now consider to be the best embodiment thereof, I desire to have it understood that the mechanism shown is merely illustrative and that 85 such changes may be made when desired as fall within the scope of the appended claims.

Having thus described my invention, I claim as new and desire to secure by Letters Patent:

1. The combination of a gate, a pair of links forming a toggle device for opening and closing the gate, said links being in alignment or dead center position when the gate is closed, means connected with the 95 links to collapse the toggle device for opening the gate, a self-setting latch mounted to engage the gate when in open position, and automatic means operatively connected with the said means for releasing the latch, 100 whereby the toggle device automatically closes the gate.

2. The combination of a gate, a pair of links forming a toggle device for opening and closing the gate, said links being in 105 alignment or dead center position when the gate is closed, means connected with the links to collapse the toggle device for opening the gate, a self-setting latch mounted to engage the gate when in open position, and automatic means for releasing the latch, whereby the toggle device automatically 110 closes the gate, said means including a time-controlled device arranged to move against and release the latch to effect the closing of 115 the gate.

3. The combination of a gate, an upwardly folding toggle device consisting of hingedly connected link members, a ball and socket joint between one end of the toggle 120 device and gate, said toggle device being adapted to occupy a horizontal position when the gate is closed, a support to which the other end of the toggle device is hingedly connected on an axis at an angle to the 125 horizontal, whereby the toggle device collapses upwardly to open the gate, a latch for holding the gate open with the toggle device in an unbalanced position, whereby it will automatically close the gate when the 130

latch is released, and automatically operated means for releasing the latch.

4. The combination of a gate, an upwardly folding toggle device connected with the gate for opening and closing the same and adapted to assume a position to normally lock the gate closed, a latch for holding the gate open, and a time-controlled mechanism operatively connected with the 10 said device automatically set simultaneously with the opening of the gate and adapted to release the latch to permit the gate to automatically close after the lapse of a predetermined interval.

15 5. The combination of a road gate, an upwardly folding toggle mechanism for opening and closing the same, a latch for holding the gate open, a gravity-operated means for releasing the latch, and a timing device 20 operatively connected with the said mechanism for controlling the said means, whereby the gate closes after the lapse of a predetermined interval from the opening of the gate.

25 6. The combination of a gate, an upwardly folding toggle device connected with the gate for opening and closing the same, a

pull cable connected with the device, a latch for holding the gate open, a time-controlled means for automatically releasing the latch 20 after the lapse of a predetermined interval, and means for automatically setting the last-mentioned device with the operation of the pull cable.

7. The combination of a gate mounted to 35 swing on a vertical axis at one end of the gate, a toggle device consisting of a pair of links pivotally connected, a ball and socket joint between the toggle device and gate, 40 said toggle device being adapted to break upwardly, a fixed support, and a hinge between the support and the end of the toggle device opposite from the gate, said hinge having its pivotal axis at an angle to permit the gate end of the toggle device to 45 swing in an arc of a circle concentric with the vertical axis on which the gate swings.

In testimony whereof I have signed my name to this specification in the presence of two subscribing witnesses.

EUGENE PHELPS.
